UNITED STATES PATENT OFFICE.

JOHN H. FOX, OF NEW YORK, N. Y.

BOTTLE-CAPPING MACHINE.

SPECIFICATION forming part of Letters Patent No. 702,716, dated June 17, 1902.

Application filed August 6, 1901. Serial No. 71,060. (No model.)

To all whom it may concern:

Be it known that I, JOHN H. FOX, a citizen of the United States, residing at 234 East Thirty-third street, New York, county of New York, State of New York, have invented certain new and useful Improvements in Bottle-Capping Machines, fully described and represented in the following specification and the accompanying drawings, forming a part of the same.

The object of the present invention is to greatly cheapen and simplify the construction of bottle-capping machines by avoiding the use of automatic feeding devices and 15 clenching devices. This is effected by using a simple tapering socket carried by an imperforate spindle and placing the crowns successively in such socket by hand. Where the 20 crowns are fed to the socket automatically, they are introduced through a lateral passage above a sustaining-collar, through which the neck of the bottle is inserted, and the contraction of the crown, which is caused by crimping it upon the bottle-neck, enables 25 it to pass through such aperture after it is secured upon the bottle. Such a construction cannot be used in my invention, in which the 30 crowns are placed in the open mouth of the socket by hand, and to permit such introduction of the crowns I provide the lower end or 35 face of the socket at one side of its aperture with a pivot and hinge a movable collar thereon, which may be turned sidewise from the aperture to introduce the crown into the 40 socket and pushed back beneath the aperture to support the crown while the bottle is capped. The aperture in the collar is of suitable size to introduce the bottle-neck and to 45 clear the crown after it is crimped thereon, so that the bottle can be pushed up through 50 the collar and drawn downward through the same with the crown attached.

In the annexed drawings, Figure 1 is a side elevation of the apparatus with its frame attached to a vertical post. Fig. 2 is a front elevation of the apparatus detached from the post and the cap compressed upon the mouth of the bottle. Fig. 3 shows the under side of 55 the socket with the retaining-collar swung to one side and a cap inserted in the socket in readiness to secure by the collar. Fig. 4 is a

cross-section of the collar on line 4-4 in Fig. 3. Fig. 5 is an edge view of the cap with a section of the socket. Fig. 6 is a vertical section of the socket, cap, and collar applied to the bottle-mouth in readiness for closing the flange upon the bead of the bottle-neck. Fig. 7 is a plan of the table with the gage for centering the bottle and the frame-plate shown in section on line 7-7 in Fig. 2.

a designates the frame-plate or bed of the apparatus shown, attached to a post *b*, which supports it vertically in a convenient position to use the apparatus.

c designates a table for supporting the bottle *A* and having a foot *d*, provided with vertical slots *e*, from one side of which lateral recesses *e'* are extended to receive bolts *f*, which are fixed in the plate *a* and projected through the slots. The lateral recesses are formed at 60 different points of elevation in the sides of the slots and are thus adapted to firmly support the table in certain definite positions when the lateral recesses are pressed upon the bolts and the foot of the table clamped by the thumb-nuts 65 on the bolts, which are shown only in Fig. 1. The table may thus be set to bring bottles of certain definite heights into operative relation to the capping-socket and is held firmly in such definite positions by the engagement 70 of the lateral recesses with the bolts. This means of adjustment requires no gage to set the table nor any skill on the part of the operator to avoid improper adjustment, as the lateral recesses are designed to automatically 75 set the table in positions corresponding to bottles of different heights, which are adapted for capping by the application of the socket when set upon the table in such positions. Such notched slots have been used in connection with a round spindle fitted to a round 80 guide; but the object of my construction is to avoid the necessity of any guide to set the table level, which I accomplish by providing two slots near opposite edges of the foot *d* and 85 making the recesses or notches *e'* in both slots at coincident levels.

A U-shaped gage *h* is projected from the frame-plate near the table to center the bottle, and its opening is made large enough to 90 receive the largest bottle to be capped, and the same apparatus may be used (without

change) to cap bottles of the same class which do not vary greatly in diameter and height. A vertical guide *i* is formed at the top of the frame-plate *a* at a suitable distance from the 5 plate to stand over the center of the bottle, and a spindle *j* is fitted thereto and provided at the lower end with the socket *k* to receive the cap *l*. The cap is shown in Fig. 6 with a cork lining *w*. The spindle is formed with a 10 shoulder, and a spring *n* is inserted between the shoulder and the guide *i* to normally raise the socket.

A hand-lever *p* is hinged by a link *q* to the frame-plate *a* and is pivoted by bolt *o* to a 15 joint upon the spindle, and the depression of the hand-lever compresses the spring *n* and forces the socket toward the bottle-neck.

The socket, as shown in Figs. 3 and 6, is formed with an interior recess *s*, which is 20 slightly tapered internally and its mouth or outer edge rounded to admit the flange of the cap, which is flared outwardly, as shown in Fig. 5, and corrugated or ribbed upon its margin to facilitate its compression upon the 25 bottle-neck. A retaining-collar *r* is jointed by a pivot *t* upon the face of the socket and may be turned to slide over the same, and thus retain the cap when placed in the socket, as shown in Fig. 6. The collar is formed with 30 round central aperture *r'*, a little smaller than the flange of the cap, so as to retain the cap in the socket, but larger than the diameter of the cap after compression, which permits the cap to be readily drawn from the socket when 35 the bottle is removed with the cap compressed thereon. A pin *u* (shown upon the socket in Fig. 3) serves as a stop to set the aperture *r'* concentric with the socket, and the collar is provided with a short handle having a hole *v*, 40 in which a bent hook may be inserted to turn the collar if it becomes jammed by the displacement of a cap within the socket.

The rounded corner of the recess *s* is formed of such size that the collar *r* crowds closely 45 over the cap when turned to retain the same; but the inner surface of the collar is slightly recessed or beveled toward its central aperture *r'*, as shown in Fig. 4, which affords a little clearance for the flange of the cap as it 50 is drawn inwardly when pressed upward into the socket. Fig. 5 shows the socket with the taper confined to the outer edge of the recess *s*, the remainder of the recess being cylindrical or parallel, and such form produces precisely the same effect as the socket 55 having the tapered recess, as shown in Fig. 6, as the rounded corner of the recess forces the flange of the cap inwardly and incloses it upon the bottle-neck, as desired.

60 The apparatus is operated as follows: The operator inserts a cap in the socket with the collar moved to one side, as shown in Fig. 3, and the collar is then turned beneath the cap, as shown in Fig. 6. The movement of 65 the socket toward the bottle-neck operates to force the cap upward into the socket, the resistance of the flange first tightly crowd-

ing the cork *w* against the neck of the bottle, thus firmly closing its mouth. When the compression of the cork develops sufficient 70 resistance to compress the flange of the cap, the cap is crowded upwardly into the recess *s* and the tapering sides or flaring mouth of the socket crowd the corrugations upon the flange inwardly and lock them around the 75 bead *B*. Such compression of the flange reduces its diameter, so that when the socket is lifted by releasing the pressure upon the handle *p* the cap may be readily withdrawn through the aperture *r'*, attached to the bead 80 upon the bottle.

Having thus set forth the nature of the invention, what is claimed herein is—

1. The bottle-capping machine having a 85 table for supporting the bottle, the socket *k* having recess *s* with its outer edge adapted to crowd inwardly the flange of the cap, the pivot *t* upon the face of the socket at one side of the recess, with the collar *r* pivoted thereon and movable laterally over the recess, and 90 having central aperture *r'* a little smaller than the flange of the cap to sustain the cap when placed in the socket, and means for pressing the socket upon the bottle-mouth.

2. The bottle-capping machine having a 95 table for supporting the bottle, the socket *k* having recess *s* with its outer edge adapted to crowd inwardly the flange of the cap, the pivot *t* upon the face of the socket at one side of the recess, with the collar *r* pivoted 100 thereon and movable laterally over the recess, and having central aperture *r'* a little smaller than the flange of the cap to sustain the cap when placed in the socket, but such aperture 105 being larger than the diameter of the cap after compression, whereby the bottle-neck may be inserted through the collar and withdrawn therefrom with the compressed cap thereon.

3. The bottle-capping machine having a 110 table for supporting the bottle, the socket *k* having recess *s* with its outer edge adapted to crowd inwardly the flange of the cap, the pivot *t* upon the face of the socket at one side of the recess, with the collar *r* pivoted thereon and 115 movable laterally over the recess, and having central aperture *r'* a little smaller than the flange of the cap to sustain the cap when placed in the socket, the stop-pin *u* upon the 120 face of the socket to adjust the collar with its aperture *r'* concentric with the socket, and means for pressing the socket upon the bottle-mouth.

4. The bottle-capping machine having a 125 table for supporting the bottle, the socket *k* having recess *s* with its outer edge adapted to crowd inwardly the flange of the cap, the pivot *t* upon the face of the socket at one side of the recess, with the collar *r* pivoted thereon and 130 movable laterally over the recess, and having central aperture *r'* a little smaller than the flange of the cap to sustain the cap when placed in the socket, and the collar being sloped upon its inner side near the aperture

r' to afford clearance for the flange of the cap when the collar is slid under the cap, substantially as herein set forth.

5. The bottle-capping machine herein shown and described, comprising the flat frame-plate a for attachment to the post, the table c secured upon such plate, the vertical guide i upon the top of the plate, the spindle j movable vertically in such guide and having the 10 socket k upon its lower end with pivot t and stop-pin u upon the face of the socket, and collar r hinged upon such pivot with aperture r' set concentric with the socket by the stop-pin, the shoulder formed upon the upper part 15 of the spindle with spring n inserted between the shoulder and the guide i , and the hand-lever p pivoted to the spindle with link q hinging the same to the plate a , the whole being adapted to have the cap placed in the 20 socket by hand, the collar turned to support the cap, the bottle sustained upon the table,

and the cap attached to the bottle by depressing the hand-lever, substantially as herein set forth.

6. The bottle-capping machine herein shown 25 and described, comprising the flat frame-plate a having upon its upper end the guide i with spindle j having socket to cap the bottles, and the table c with foot d fitted to the frame-plate with bolts extended through the plate and the 30 foot, and the foot having two vertical slots e with lateral recess e' at coincident levels, to engage the bolts in specific positions of the table and to hold the table level in such positions, substantially as herein set forth. 35

In testimony whereof I have hereunto set my hand in the presence of two subscribing witnesses.

JOHN H. FOX.
